Mr. W. P. Woodward, Maryland

7804X

Letters Patent

The Schedule referred to in these Letters Patent and making part of the invention
bearing a description in the words of the said William W. Woodward, being, to
his improvement in the machine for sawing felloes for carriages, which consists of
shingles running length and the work is straight work. — — —

It is known that William Woodward of Harford County State of
Maryland has made an improvement in the machine for sawing
felloes for carriage wheels, chain tops, shingles, tenoning blocks, and other
curved or straight work, which is described as follows. — — —

The frame is made of timber ten feet long, four feet
high to the top, two inches wide with eight posts each 4 by 5 inches thick
baffon inside and placed nine inches apart, mortised into top plates
at the sides. The board is made wide nine inches thick and let into the top
plates opposite one the inside posts placed nine inches apart for the
carriage to stand on. A nail tie is mortised into each top plate three
or four inches from the end. A piece of timber is mortised into the end
by one end in the centre having of each, & the other end joined to the board
which support the carriage. — — —

The carriage is in the shape of a segment of a
circle. The piece is cut off on which is fixed a head block near each end, to
receive a peg for holding the block of timber to be clamped which
peg can be driven into the block by a wedge or otherwise. A tongue
let into the centre of the chord of the carriage with holes in it at different
distances from either of which a pin can be inserted into the piece of
timber for the purpose of carrying the size of the circle. — — —

A slot is made in the carriage from side
to side the one and parallel with it for the wheel to run thru. — a cord is
attached to one of the carriage passing around the pegs and over a thimble run
down to the rag wheel. There are four pegs four feet long and two
and a half inches of each for the purpose to run them set so far in from

apart to allow the weight of the down from both really thin. The down frame
is nine inches wide and three feet long, with an arm for passing needles
long, extending from the front part to receive a long flat card and
paper similar to the last in each carriage. There is a roller on each side
extending from one needle part to the other, to each of which is attached a
ring. The rings are attached to the down frame so the ends of the other in a
mortise to regulate the feed. One of the rollers is a tongue, placed on each side
of the center tongue & which is called compound to work the rag to the card.

The machine is operated by the hand, mainly by a pulley
and shaft with flywheel and driving wheel.

For a further illustration of my invention I refer to the model
and drawing of the same in the Patent Office.

I now declare my invention more clearly, distinctly,
and fully than I have done in my application, by
setting forth the construction and arrangement of the several parts of the
above described machine for cleaning, picking, and the parts themselves.

In testimony whereof I have this day signed this
